UNITED STATES PATENT OFFICE

CARL C. HARRIS, OF ORANGE, MASSACHUSETTS

FINGER MOISTENER

Application filed May 23, 1928. Serial No. 280,003.

This invention relates to a moistener for the fingers for use in offices and the like.

The principal objects of the invention are to provide a moistener in the form of a substance which will retain the moisture and keep it at the surface; to construct this moistener of such shape as to enable the whole moistener to be filled with water or moistened without removing the moistening element; to provide a space into which the water can be poured; and also to provide such a space for receiving the fingers when they are being moistened.

Reference is to be had to the accompanying drawings in which

Fig. 1 is a plan of the moistening element by itself; and

Fig. 2 is a sectional view of the moistener complete.

20 I have shown the moistener as located in a cup 10 which may be of any desired construction. This cup is provided with spurs 11 inside for a purpose to be described.

The moistening element 12 consists of a 25 piece of sponge rubber. Its vertical walls fit within the cup 10 and the spurs 11 project into the surface of the sponge rubber to keep it from being accidentally displaced.

The sponge rubber element preferably projects materially above the top of the cup and it is provided with an opening 13 preferably in the center and conveniently of a conical shape. This opening extends, preferably, all the way from the top to the bottom as shown, 35 but at any rate it leaves a recess in the sponge rubber into which the water can be poured when filling the moistener and which will have slanting surfaces for engagement of the fingers of the operator.

40 In use the sponge rubber element does not have to be previously moistened, but can be placed in the cup and kept there. The water is poured in through the central opening 13 and will permeate all parts of the rubber element and the moisture will always be where it can be applied to the fingers by merely rubbing the fingers along this surface. The opening in the center not only is to receive the water when poured in and keep it from 45 spreading around the surface of the moisten-

ing element, but constitutes an extremely convenient surface for the contact of the fingers of the user in moistening.

Although I have illustrated and described only a single form of the invention, I am 55 aware of the fact that changes can be made therein by any person skilled in the art without departing from the scope of the invention as expressed in the claims.

Therefore, I do not wish to be limited to the 60 exact form shown, but what I do claim is:—

1. As an article of manufacture, a finger moistener comprising a sponge rubber element having an unobstructed opening extending down into its top surface for receiving 65 water and furnishing a convenient surface accessible from the top for contact with the fingers of the user.

2. As an article of manufacture, a finger moistener comprising a piece of sponge rubber having a tapering opening through its center extending all the way from the top to the bottom and having its walls of the same material as the rest of the moistener.

3. As an article of manufacture, a finger moistener comprising a cup having vertical inner walls, and a moistening element having vertical walls engaging the walls of the said cup, said element extending above the cup and having an opening down through it to 75 the bottom of the cup.

4. As an article of manufacture, a finger moistener comprising a cup having spurs extending inwardly from its sides, and a moistening element comprising a piece of sponge rubber having vertical walls engaging the walls of the said cup and receiving said spurs to hold it in position, said sponge rubber element extending above the cup and having an opening down into it.

In testimony whereof I have hereunto affixed my signature.

CARL C. HARRIS.
